[57] CLAIM

The ornamental design for a RF thermometer receiver, as shown and described.

DESCRIPTION

FIG. 1 is a front elevational view of the RF thermometer receiver of the present invention;

FIG. 2 is a back elevational view of the RF thermometer receiver of the present invention;

FIG. 3 is a top plan view of the RF thermometer receiver of the present invention;

FIG. 4 is a bottom plan view of the RF thermometer receiver of the present invention;

FIG. 5 is a right side elevational view of the RF thermometer receiver of the present; and,

FIG. 6 is a left side elevational view of the RF thermometer receiver of the present invention.
